WATER HEATING APPARATUS

Ralph B. Davis, Prestonsburg, Ky.

Application May 6, 1943, Serial No. 485,922

3 Claims. (Cl. 122—16)

This invention relates to improvements in water heating apparatus.

The primary object of the invention is to provide a stand boiler with a water heating apparatus or attachment which will operate with maximum efficiency in maintaining a supply of hot water in the boiler.

Another object is to provide a water heating apparatus or attachment for stand boilers in which a gas burner is used for heating a series of water coils which are connected to the water supply and to the stand boiler in an arrangement that will produce maximum efficiency in the heating of the water and in the maintenance of a supply of hot water in the boiler.

More particularly, the invention contemplates a water heating apparatus wherein the water is preheated in one water coil and primarily heated in a second water coil, the water from the pre-heating coil being discharged into the stand boiler at a point in close proximity to the point at which the intake of the primary heating coil is located.

With these and other objects in view, the invention consists in certain novel details of construction and combinations and arrangements of parts, all as will hereinafter be more fully described and the novel features thereof particularly pointed out in the appended claims.

In the accompanying drawing,

Figure 1 is a sectional view taken longitudinally of a stand boiler illustrating the preferred embodiment of the present invention; and

Fig. 2 is a similar view illustrating a modified form of the invention.

In Fig. 1, the stand boiler 10 is of tubular formation, having a flue 11 of uniform cross-section extending axially thereof which constitutes a passage for products of combustion from the gas burner 12 mounted in any suitable manner adjacent the lower end of said flue. Immediately above burner 12, there is mounted in flue 11 a water coil 13 which is termed the primary heating coil, as the water passing therethrough absorbs the major portion of the heat from the burner. The intake or lower end 14 of this primary heating coil is located adjacent the lower end of the stand boiler, and said coil discharges into the upper end of the boiler, an extension 15 being provided on the upper end of the coil proper for this purpose.

Also mounted in the flue 11, at a point above the primary coil 13, is what is termed the preheating coil 16. Water from a source of supply enters the upper end of this coil and is discharged from the lower end through an extension 16a which termi-

nates at a point or level within the boiler which substantially corresponds to the level at which the intake 14 of the primary heating coil 13 is located.

With this arrangement of the heating coils 13 and 16, the maximum heating effect of burner 12 will be obtained by reason of the fact that a great deal of heat that would ordinarily be lost is absorbed by the water in the upper water coil 16. The provision of this preheating coil 16 has the further advantage of preventing water entering the boiler at the temperature of the water in the service line. This, of course, increases the efficiency of the boiler and of the heating apparatus as a whole. Furthermore, the preheated water is discharged from coil 16 into the lower portion of the boiler from which coil 13 draws its supply, so that the water, heated to a higher temperature in the top portion of the boiler, is less likely to be affected by the incoming water which is of lower temperature. Thus, when hot water is drawn from the boiler through the outlet 17 in the top of said boiler, water will flow from the lower portion of the boiler into primary heating coil 14 which will, at the same time, be emptying hot water into the upper end of the boiler, and a fresh increment of water will flow into the preheating coil 16 as the latter empties water which has been heated to some extent into the bottom of the boiler. As stated, this particular arrangement of the two coils greatly increases the efficiency of the boiler, not only by reason of the absorption of a major portion of the heat from burner 12, but also by reason of the specific manner in which the water is circulated through the coils and boiler.

If desired, an adjustable closure 18 may also be provided at the discharge end of flue 11 to conserve the heat from burner 12 and slightly increase the efficiency of the apparatus.

In the form of apparatus illustrated in Fig. 2, the coils 13, 16, and burner 12, are housed in flue or passage 11a located exteriorly of the boiler 10 and preferably covered with heat insulating material 19. In this arrangement, the fresh supply of water enters preheating coil 16 at the bottom thereof and the upper end of said coil is provided with an extension 16a which terminates in the lower portion of the stand boiler. As in the previously described arrangement of Fig. 1, the primary water heating coil 13 of this modification draws water from the bottom portion of the boiler and discharges into the upper end of said boiler.

What I claim is:

1. In a water heating apparatus for stand

boilers, the combination of a stand boiler having a vertical flue of uniform cross-section extending therethrough, a gas burner located in the lower end of said flue, a preheating water coil located entirely within said flue, said coil having its supply end located at the upper end of the flue, a discharge connection at the lower end of said coil terminating in the lower portion of the stand boiler, a primary water coil located entirely within said flue intermediate said preheating coil and said burner, the intake of said primary coil being connected to the flue at the lower end thereof and the discharge of said primary coil being connected to the upper end only of the flue, and a discharge connection in the upper end of said boiler.

2. In a water heating apparatus for stand boilers, the combination of a stand boiler having a vertical flue extending therethrough and terminating at the upper and lower ends of the boiler, a gas burner in the lower end of said flue, a preheating water coil located entirely within said flue and having a discharge extension on its lower end terminating in the bottom portion of said boiler, the upper end of said preheating coil being adapted to be connected to a source of water supply, a primary water heating coil located entirely within said flue inter-

mediate said burner and said preheating coil, the intake and outlet of said primary coil being connected to the lower and upper portions, respectively, of said flue, and said boiler having a discharge outlet in its upper portion, said discharge outlet being the sole means of supplying water from said boiler.

3. In a water heating apparatus for stand boilers, the combination of a gas burner having a vertical flue of uniform cross-section associated therewith for products of combustion, a preheating water coil to which water to be heated is supplied, said coil being located entirely within said flue and said coil having a discharge located in the lower portion of the boiler, a primary water coil located entirely within said flue intermediate said preheating coil and said burner, the intake of said primary coil being connected to the flue at the lower end thereof and the discharge of said primary coil being connected solely to the upper end of the flue, a discharge connection constituting the sole line of discharge from the upper end of said boiler, and a damper at the upper end of said flue for adjustably controlling the flow of gases from the burner through the flue.

RALPH B. DAVIS.
